UNITED STATES PATENT OFFICE.

FREDERICK WILLIAM SCHROEDER, OF STRAND, LONDON, ENGLAND.

RIB AND RIB-JOINT FOR UMBRELLA AND PARASOL FRAMES.

No. 874,799.

Specification of Letters Patent.

Patented Dec. 24, 1907.

Application filed May 7, 1907. Serial No. 372,402.

To all whom it may concern:

Be it known that I, FREDERICK WILLIAM SCHROEDER, a subject of the King of Great Britain, residing at 9 Arundel street, Strand, 5 in the county of London, England, engineer, have invented certain new and useful Improvements in Ribs and Rib-Joints for Umbrella and Parasol Frames, of which the following is a specification.

10 This invention relates to an improvement in the construction of **U**-shaped ribs for umbrella and parasol frames and to improved constructions of joints for connecting the stretcher ribs to the frame ribs, whereby the 15 ribs are enabled to lie more compactly together when closed and the joints are rendered less liable to wear out the fabric of the umbrella or parasol.

In the accompanying drawings Figure 1 20 shows a perspective view of one construction of joint with the parts assembled as applied to the improved construction of rib according to the present invention, Figs. 2, 3 and 4 show details of this joint to an enlarged 25 scale, and Fig. 5 shows a cross section of the said joint with the parts assembled together; Fig. 6 shows the improved construction of joint with the parts assembled when applied to an umbrella **U** rib of ordinary construction.

The improvement in the construction of the grooved rib consists in manufacturing this of thinner metal, the strengthening thereof being effected by grooving, corrugating, or ribbing both sides of the grooved rib *a* along its entire length as shown at *a'* in Figs. 1, 2 and 5.

In the case of the employment of a ribbed, grooved or corrugated **U**-shaped rib such as 40 above referred to, the joint is constructed as shown in Figs. 1 to 5. The outer end of the **U**-shaped stretcher rib *b* which may also be grooved or corrugated, is pressed together, and a small hole *c* is drilled or 45 punched at the end thereof. This is then placed in a piece of sheet metal *d* doubled over on itself, forming a **U**-shaped piece, the sides of which are of greater depth than the corrugated grooved rib *a*. This piece of 50 sheet metal may also be corrugated so as to form a rib *d'* on each side when doubled over on itself (Fig. 5) or it may simply have holes indented on it so as to form outer projections *d''* on each side (Fig. 3), which ribs *d'* or projections *d''* fit into the groove *a'* when the piece *d* is slid into the grooved rib *a*.

As shown in Figs. 1, 3 and 6, the sides of the joint piece *d* extending beyond the edge of the main rib may be formed with shoulders *d⁴* abutting on the edges of the sides of the 60 rib *a*.

The parts having been assembled as shown in Figs. 1 and 5, an indentation or hole *e* is punched on each side opposite the hole *c* of the stretcher rib, in such a manner 65 that the metal burs or edges of these holes *e* protrude into the hole *c*, thus forming a pivot on which the stretcher rib *b* can be moved backwards and forwards.

The indenting or punching of the hole *e* is 70 also arranged to be punched in such a position as to indent or punch in at the same time the edge of the outer grooved rib *a* which prevents the longitudinal movement of the hinged joint, its movement outwardly 75 from the rib *a* being prevented by the ribs *d'* or projections *d''* being held by the groove *a'*.

When a **U** rib of ordinary construction is employed, as in Fig. 6, the **U**-shaped piece *d* is made without the ribs *d'* or projections *d''* but 80 of somewhat greater length with indentations or holes *d²* at each end, and when placed in position is secured from both longitudinal and outward movement in the rib by indenting the sides of the outer rib at *f* opposite 85 the end holes or indentations in the piece *d*.

Having thus described the nature of this invention and the best means I know of carrying the same into practical effect, I claim:— 90

1. In umbrella frames a main rib of substantially **U**-shaped section, a joint piece of substantially **U**-shaped section adapted to fit within the said rib, but having its sides projecting beyond the edges of the sides of 95 the rib, locking indentations in the sides of the rib and of the joint piece, inwardly projecting indentations in the projecting portion of the joint piece, and a stretcher rib having its end formed to engage pivotally 100 with the said inwardly projecting indentations; substantially as described.

2. In umbrella frames, a rib of substantially **U**-shaped section but having the sides thereof formed with longitudinal corrugations to strengthen said rib; substantially as 105 described.

3. In umbrella frames, a main rib of substantially **U**-shaped section but having the sides thereof formed with longitudinal corrugations, a joint piece of substantially **U**-shaped section adapted to fit within the said 110

rib and having indentations engaging the said corrugations, a stretcher rib having a transverse hole formed in the end thereof, and inwardly projecting indentations in the 5 sides of the joint piece engaging the hole in the stretcher rib; substantially as described.

4. In umbrella frames, a rib of substantially U-shaped section but having the sides thereof formed with outwardly projecting 10 longitudinal corrugations, a joint piece of substantially U-shaped section having outwardly projecting longitudinal corrugations engaging the corrugations in the rib, said joint piece being inclosed within the sides of 15 the rib but having its sides extending beyond

the edges of the sides of the rib, and having shouldered portions abutting on the said edges, inwardly projecting indentations in the said shouldered portions of the joint piece, and a stretcher rib having its end 20 formed to engage pivotally with the said inwardly projecting indentations; substantially as described.

In testimony whereof I have signed my name to this specification in the presence of 25 two subscribing witnesses.

FREDERICK WILLIAM SCHROEDER.
